(57) **CLAIM**

The ornamental design for a tire inflation kit, as shown and described.

DESCRIPTION

FIG. 1 is a top perspective view of a tire inflation kit, according to one preferred embodiment of the invention;

FIG. 2 is a front view of the tire inflation kit shown in FIG. 1;
FIG. 3 is a rear view of the tire inflation kit shown in FIG. 1;
FIG. 4 is a top view of the tire inflation kit shown in FIG. 1;
FIG. 5 is a bottom view of the tire inflation kit shown in FIG. 1;

FIG. 6 is a left side view of the tire inflation kit shown in FIG. 1;

FIG. 7 is a right side view of the tire inflation kit shown in FIG. 1; and

FIG. 8 is a top perspective view of the tire inflation kit shown in FIG. 1.

The broken lines are included for the purpose of illustrating portions of the tire inflation kit that form no part of the claimed design.

1 Claim, 6 Drawing Sheets
